UNITED STATES PATENT OFFICE.

ENOCH WAITE, OF FRANKLIN, MASSACHUSETTS.

PACKING FOR CAR-AXLE BOXES.

SPECIFICATION forming part of Letters Patent No. 336,966, dated March 2, 1886.

Application filed August 3, 1885. Serial No. 173,376. (No model.)

To all whom it may concern:

Be it known that I, ENOCH WAITE, of Franklin, county of Norfolk, State of Massachusetts, have invented certain new and useful Improvements in Lubricant-Packing for Bearings, of which the following is a full, clear, concise, and exact description, reference being had to the drawings accompanying and forming a part hereof, in which—

10 Figure 1 is a central lengthwise section through a railway-car axle and box with my improved packing applied. Figs. 2, 3, and 4 are details.

The object of my invention is the construction of a lubricant vehicle or packing which shall possess great absorbent quality and at the same time be compact, light, and cheap, and not liable to be worn away or destroyed rapidly; and it consists in fibrous felted or 20 woven material in the shape shown and hereinafter more fully described.

Like letters of reference indicate like parts. A is the axle, and B the axle-box, which contains beneath the axle a lubricant-chamber. 25 As at present commonly used this chamber is filled with waste which has been saturated with oil, and the objections to a packing of waste are that it sags down after a short use, and is liable to settle clear of the axle; it does 30 not retain the oil with which it is saturated, but allows it to escape through the box; some of its threads are liable to get wound around the axle and by friction ignite, and it is also frequently gritty from sand and foreign material 35 and operates to roughen or cut the bearing. To obviate these difficulties, I construct my packing from strips *d* of felt of any desired width, which are laid side by side, so that the cut edges of the strips form the surface of the 40 block or piece D. This block D is made of sufficient width to fill the box and deep enough to fill the space between the bottom of the box and the axle. If desired, it may be of less depth, and may have a strip of wood or other 45 material, E, placed under it, as shown, to hold it up against the axle. The strips forming the block are secured together in any suitable manner. I prefer, however, to use a piece of cord, *a*, which is run through them by the aid 50 of a needle and the ends tied, as shown. The

block thus formed is flexible, absorbent, and yields the lubricant to the axle readily, acting as a series of fine brushes. For some purposes, as in lubricating the axle-bearings of locomotive driving-wheels, I use this block 55 alone in the box; but for car-axles I prefer to place a separate piece, F, cut in a shape to fill the back of the box and fit closely around the axle. This intercepting piece prevents sand or dust from entering the inner end of the box, 60 and also tends to keep any surplus oil from escaping from the box. I also place a flat piece of felt, H, in the front part of the box just inside the door, which acts in like manner to protect the lubricant packing and axle from 65 sand or other foreign matter entering at the outer end of the box. The lubricant packing, being in one block or piece, may be easily put into the box or withdrawn from it, and, being flexible and compressible, may be crowded into 70 and made to fill the box throughout the space underneath the exposed portion of the axle.

As will be obvious, other fibrous material may be substituted in my packing for felt— 75 as, for example, a series of layers of woven fabric secured together to form a thick bat, which may be cut into strips and used to construct my packing. I prefer felt, however, as being the most desirable substance for this use.

I am aware that felt has been used for lubricant-packing. Such a use of it is shown in Letters Patent to P. S. Devlan, No. 113,860, dated April 18, 1871, and I do not therefore claim it, broadly.

I am also aware that packing-pads of felt or other material have heretofore been used in journal-boxes, as shown by patent to S. A. Bemis, No. 306,572, dated October 14, 1884; but in such case the pads were placed so that the material impinged flatwise against the 90 journals, thus compressing the packing in such a manner that the lubricant could not flow so freely to the journal as in my arrangement with the packing material having its cut edges presented to the journal.

What I claim is—

1. The combination, with a car box and axle, of a lubricant-packing consisting of a block formed of a series of strips of felted or woven fibrous material laid and secured together, and 100

an intercepting layer filling the rear portion of the box and fitting closely around the axle, for the purposes and substantially as described.

2. The combination, with a car box and axle, 5 of a block for supplying the lubricant to the bearing, consisting of a series of strips of felted or woven fibrous material laid and secured together, and a protecting piece of the

same material laid against the end of the axle, whereby the axle and packing are protected from sand and dust, substantially as shown and described.

ENOCH WAITE.
